UNITED STATES PATENT OFFICE.

OLIVER E. DE RIDDER, OF ROCHESTER, NEW YORK.

METHOD OF MAKING SHOES.

Application filed January 20, 1923. Serial No. 613,995.

To all whom it may concern:

Be it known that I, OLIVER E. DE RIDDER, a citizen of the United States, and resident of Rochester, in the county of Monroe and State of New York, have invented certain new and useful Improvements in Methods of Making Shoes, of which the following is a specification.

The present invention relates to a method 10 of making shoes and more particularly to the type in which the inner sole of the shoe is moistened and molded by pressure while moistened to a desired shape, the upper thereafter being stitched to the inner sole 15 and the other operations of the shoe being completed. An object of this invention is to provide for utilizing the last on which the shoe is made as one of the mold elements, making it unnecessary to handle the inner 20 sole free from the last after the molding operation. Still another object of the invention is to make one of the mold elements of yielding material so that during the molding operation, the outline of the inner 25 sole is not distorted.

Other and further objects will appear in the following description and will be more particularly pointed out in the appended claims.

30 In the drawings:

Fig. 1 is a side view of a last with an inner sole attached thereto before the molding operation;

Fig. 2 is a side view of the last with the 35 inner sole attached thereon and cooperating with the yielding mold element which is shown in section and under compression;

Fig. 3 is a section on the line 3—3, Fig. 2;

Fig. 4 is an enlarged sectional view on 40 the line 4—4, Fig. 9;

Fig. 5 is a sectional view through a shoe before the outer sole is applied;

Fig. 6 is a similar section showing the outer sole applied;

Fig. 7 is a side view of a completed shoe 45 constructed in accordance with this invention, the bottom being flat as in an ordinary shoe;

Fig. 8 is a view of the upper side of the 50 inner sole after the latter has been molded; and

Fig. 9 is a plan view of the yielding mold.

In carrying out this invention, the last 1 55 is shaped on its under side in any suitable manner being preferably provided with two projections 2 and 3, with a depression 4 be-

tween them, thus simulating in effect the under side of the foot at the metatarsal arch. The heel may also be provided with a convex portion 5 simulating the heel of the 60 foot, while the arch portion 6 is formed to simulate the arch of the foot.

An inner sole preferably the well-known solid leather inner sole is provided which around its sides and toe portion is reduced at 65 7 to provide the usual shoulder 8 and is cut parallel with said shoulder by a kerf 9. Before the molding operation this completed inner sole is moistened, preferably thoroughly wet, so that it becomes adapted to a molding 70 process. While in the moistened condition, it is tacked to the last in the usual manner as illustrated in Fig. 1, covering the bottom of the last in a loose condition. While still moist and on the last it is subjected to the molding operation. This is effected 75 preferably through a molding element which is formed of a yielding material so that such element will readily adapt itself to the contour of the last and cause 80 the inner sole to become shaped to the under side of the last, and thereby provide a shape on its upper side to fit the contour of the bottom of the foot.

In this instance, the yielding molding element illustrated in Figs. 2, 3, 4 and 9 embodies a block 10 of rubber which has a depression 11 conforming substantially to the forepart of the last and the forepart of the arch, this depression having a projection 12 90 so situated that it will enter between the two projections on the bottom of the last or upper mold member, thus insuring that the inner sole will conform to the metatarsal arch of the foot. A relative movement takes 95 place between the two mold members and causes the last or upper member 1 to become embedded in the lower member 11 thus producing pressure throughout the entire inner sole and making the latter adapt itself to the 100 contour of the under side of the last.

While the inner sole is still in a wet condition, the mold members are separated and the inner sole is permitted to dry upon the last in the shape in which it has been molded. After the inner sole has become set, the upper is then attached and lasted in the usual way. After the lasting operation and 105 preferably before the inner sole has become completely dry, the lip formed between the shoulder 8 and the kerf 9 is raised and then the upper 13 is stitched as at 14 in the usual

2
manner to the lip with the welt 15. Later a
filler 16 is placed on the bottom of the inner
sole to fill all the irregularities therein, so
that a flat bottom is secured for the outer
5 sole 17 which is stitched to the welt in the
usual manner at 18. This filler prevents the
outer sole from conforming to the inner sole
and also the outer sole from breaking down
under the weight of the user of the shoe.
10 The shoe is then completed in the usual man-
ner.

From the foregoing it will be seen that
this invention makes it possible to use the
usual leather inner sole which is complete in
15 all respects before the molding operation.
This inner sole is secured directly to the last
in the first instance and in this way utilizes
the last as one of the mold elements. This
saves a great deal of time as the inner sole
20 does not require handling and at the same
time it reduces a number of the operations
and does not allow the formed inner sole to
lose its shape while drying. Furthermore
the inner sole accurately conforms to the
25 last, there being no possibility of the upper
surface of the inner sole not conforming to
the bottom surface of the last or the indentations
on the inner sole being wrongly placed.
The yielding mold prevents a crushing ac-
30 tion on the inner sole while in a moistened
condition and particularly on the edges
thereof which would tend to squeeze the in-
ner sole out beyond its normal outline and
provide a distorted edge, as a shoe, to be
35 accurately made, must have its inner sole
conform exactly to the bottom of the last
and the shoulder maintain its line perfectly.

What I claim as my invention and desire
to secure by Letters Patent is:

1. A method of making shoes which con-
sists in providing a complete inner sole with
a shoulder and a kerf, moistening said inner
sole, attaching the inner sole to a last, ap-
plying pressure to the inner sole, while in a
moistened condition, to cause the inner sole
40 to conform to the bottom of the last, permit-
ting the inner sole to dry on the last, so that
the shape of the inner sole is maintained
during the drying process, stitching the up-
per to the lip formed between the shoulder
45 and the kerf, and then completing the other
operations of making the shoe.

2. A method of making shoes which con-
sists in providing a last with an inner sole
50 in a moistened condition attached to the bot-
tom thereof, applying pressure through a
member of yielding material to such inner
sole to cause the inner sole to conform to
the under side of the last, stitching the up-
per to the inner sole, and then completing
55 the other operations of making the shoe.

3. A method of making shoes which con-
sists in providing a complete inner sole with
a shoulder and a kerf, attaching such inner
sole in a moist condition to a last suitably
60 shaped on its under side, applying pressure
to the inner sole by a member of yielding
material which causes the inner sole to con-
form to the bottom of the last without dis-
tortion, stitching the upper to the lip formed
65 between the kerf and the shoulder, and then
completing the other operations of making
the shoe.

OLIVER E. DE RIDDER.
